UNITED STATES PATENT OFFICE.

HARRY W. THEISS, OF LOUISVILLE, OHIO, ASSIGNOR TO SUPERIOR SHEET STEEL COMPANY, OF CANTON, OHIO, A CORPORATION OF OHIO.

FURNACE.

Application filed May 23, 1927. Serial No. 193,553.

This invention has reference to furnaces and, particularly, to the muffle type, especially adapted for heat-treating zinc coated materials.

It is an object of the invention that the furnace herein disclosed is adapted for carrying out the heat-treating process described and claimed in Letters Patent to J. L. Herman, No. 1,430,648, dated the 3rd

10 day of October, 1922.

The invention has for its principal object to provide a heat-treating furnace, adapted especially for heat-treating zinc coated materials, and which is capable of being moved next adjacent to or away from the galvanizing pot containing the zinc coating bath; whereby the furnace, or the pot, or both may be repaired, or for other purposes, as the case may be. The material receiving end of the furnace being inclined; whereby, when it is next adjacent the galvanizing pot it overlies such pot, enabling the transfer of the zinc coated materials from said pot to said furnace within a minimum amount of time, during which interval the coating has had little time to set, and in the case of sheets before the formation of a spangled surface. The resulting action of the heat-treatment by the furnace is to provide a tighter coat of the coating on and with the material; to evenly distribute the coating on the material and form an iron-zinc alloy, which gives the coating its physical properties.

The invention further comprehends a furnace especially adapted for the heat-treatment of zinc coated sheets; an improved supporting means therefor, and an improvement in the transfer of heat to the exposed surfaces of the sheets and gradual cooling of the sheets as they leave the furnace.

That the invention may be more fully understood, reference is had to the accompanying drawings forming a part of this description, illustrating a preferred embodiment of the invention, in which:

Fig. 1 is a diagrammatic view, partly in section, showing a method of zinc coating

sheets and heat-treating such sheets by the use of my improved furnace;

Fig. 2 is a plan view, partly in section, of the furnace;

Fig. 3 is a longitudinal sectional view thru the furnace, also showing its relation to a galvanizing pot;

Fig. 4 is a transverse sectional view thru the furnace, and

Fig. 5 is a cross-section of the arched roof of the receiving end of the muffle portion of the furnace.

Like characters denote corresponding parts thruout the figures.

In the drawings, the diagrammatic arrangement shown in Fig. 1, includes an acid tank *a*, a galvanizing pot *b* suitable for containing a zinc coating bath, and so constructed interiorly as to permit of the passage of sheets from the acid tank, thru said pot and to the furnace embodying my invention, normally disposed next adjacent thereto thru which the coated sheets are conveyed or conducted by the endless conveyor chains *2* and delivered to the usual cooling wheel *c*. During the passage of the coated sheets thru the furnace, the heat-treatment, to which such coated sheets are submitted, provides a tight coat of the coat on the sheet and with the sheet; prevents spangling of the coating; distributes the coating evenly on the sheets and helps form an iron-zinc alloy which gives the coating on the sheet its physical properties.

The furnace portions which are subjected to excessive heat are preferably constructed of suitable refractory material. It is constructed with an arched roof *3* extending thruout the length of the furnace and overlying the muffle portion *4*; also extending thruout the furnace and open at each end. At the receiving end of the furnace the arched roof *3* extends forward of the muffle and provides an overhanging portion *5*, to insure an immediate application of heat to the coated sheets as they leave the coating bath and are transferred to such furnace for treatment. The floor *6* of the muffle,

from its open receiving end to a point approximating the inner end of the fire-box 7, beneath the rear end portion of the muffle, is provided with the series of pairs of oppositely disposed and laterally extended spaced openings or passages 8, each communicating with a port 9 extending inwardly beneath the floor 6. The ports 9 on opposite sides of the furnace communicate with chambers 10, 10 divided by a partition wall 11, which terminates at its inner end at the inner end of the fire-box 7 and the latter has an arched roof wall 12. Also, on the floor 6 are provided the spaced longitudinal runways 13, preferably channel bars with the flanges turned upwardly, thru which the conveyer chains 2 move as they traverse the muffle 4 of the furnace, and said chains are adapted to receive the coated sheets from the pot b and convey the same to and thru the furnace and to the cooling wheel c.

The base wall 14 for the furnace extends thruout the length of the fire-box 7 and chamber 10, and for a portion of the length 25 of the chamber 10, starting at the receiving end of said furnace immediately below the muffle, said wall is inclined downwardly and rearwardly, as at 15, to a point near the inner end of said chamber 10, where such inclined wall terminates in and becomes the wall 14. At the rear or discharge end of the furnace, and in communication with the fire-box 7, there is provided a combustion port 16 into which would project a suitable burner, not shown.

The furnace walls are connected and braced by any suitable steel structure, and I prefer to face the lower outside face of the base wall 14 with a sheet metal covering 17. 40 This covering, together with channel beams 18, set in the wall 14 and inclined portion 15, and longitudinally of and below the beam 18, form or provide return run-ways for the chains 2. These chains at the front 45 or receiving end of the furnace are directed over sprocket wheels 19 carried by a shaft 20, journaled in any suitable supports, and at the rear or discharge end of the furnace are directed over sprocket wheels 21 carried by a shaft 22, journaled in any suitable supports. Either of the shafts 20 or 22 may be the operating shaft, and as such, arranged to receive power from any suitable source. That portion of the chains traversing the inclined portion 15 of the base wall of the furnace, is directed by guide rollers 23, between the sprocket wheels 20 and the run-ways formed by the channel bars 18.

An under steel structure for the furnace, 60 comprises a plurality of longitudinally and horizontally disposed and spaced I beams 24, which extend forward from the rear or discharge end of the furnace to a point short of the front or receiving end thereof and mediate the inclined portion 15, and suit-

ably connected to and braced from the steel bracing structure of the furnace.

When the furnace is set up for operation in a mill the I beams 24 rest and are adapted to have movement on the plurality of transversely disposed rollers 25 which rest and are adapted to have rolling movement on the floor rails 26. In this manner and by these last mentioned elements the furnace may be easily and quickly moved adjacent to or 75 away from the pot b, for purposes of repair of either or both the pot and furnace; the inclined base wall structure for the receiving end of the furnace permitting that portion of the furnace muffle to be moved to position 80 overlying the pot b for the purposes above explained.

The products of combustion traverse the fire-box 7 and chamber 10 and up and out thru the ports 9 and openings 8 into the 85 muffle, finding egress at the entrance end for the sheets into the furnace and also up and out thru exit openings 27 formed or provided in the arched roof 3. Such arrangement of exhaust openings or passages for the products of combustion provides for the application of the heat, at the maximum temperature, at the entrance end of the furnace and for an approximately even distribution of 90 such heat to the sheets, the sheets gradually 95 cooling toward the rear or discharge end of the muffle.

What I claim is:—

1. A furnace for heat-treating zinc-coated metallic materials, including a heat-treating 100 chamber open at both ends, a fire-box therebeneath, a partitioned chamber, also, therebeneath in communication with said fire-box and having communication with said heat-treating chamber thru a plurality of combustion passageways, an endless carrier movable thru said heat-treating chamber, guideways for said carrier in said heat-treating chamber and below said furnace, and exhaust ports in the top wall of said furnace 110 adjacent its receiving end and in communication with said heat-treating chamber, said top wall having an over-hanging portion at the receiving end of said heat-treating chamber.

2. A furnace for heat-treating zinc-coated metallic materials, including a heat-treating chamber open at both ends and partitioned from a combustion conducting chamber therebeneath, combustion passageways between said chamber and heat-treating chamber in the forward or receiving end of said furnace, an inclined body portion to adapt said furnace to overlie a coating means, an endless carrier having its conveying run in 125 the heat-treating chamber and its return run beneath the furnace, and guide ways for said carrier in the heat-treating chamber and beneath the furnace.

3. A furnace for heat-treating zinc-coated

metallic materials, comprising a body, the receiving end of which has an inclined base portion to adapt the same to overlie a coating means, said body being partitioned to provide a longitudinal heat-treating chamber open at both ends and an underlying combustion chamber, passage ways connecting said chamber and heat-treating chamber, exit openings in the top wall of said body, a carrier for conducting coated materials thru said heat-treating chamber, and supporting means for said furnace adapting it to be moved bodily next adjacent a coating means and removed therefrom.

HARRY W. THEISS.
